(57) **CLAIM**

The ornamental design for a holder for electronic cameras, as shown and described.

DESCRIPTION

FIG. 1 is a front plan view of a camera holder of my design; FIG. 2 is a rear view thereof;

FIG. 3 is bottom view thereof;

FIG. 4 is a top view thereof;

FIG. 5 is a right side view thereof;

FIG. 6 is a left side view thereof;

FIG. 7 is a right, bottom perspective view thereof;

FIG. 8 is a left, top perspective view thereof;

FIG. 9 is a front plan view of a second embodiment of the camera holder of my design;

FIG. 10 is a rear view thereof;

FIG. 11 is bottom view thereof;

FIG. 12 is a top view thereof;

FIG. 13 is a right side view thereof;

FIG. 14 is a left side view thereof;

FIG. 15 is a right top elevational view thereof; and,

FIG. 16 is a left bottom view thereof.

The broken lines depicts portions of the article that form no part of the claimed design.

1 Claim, 16 Drawing Sheets
